UNITED STATES PATENT OFFICE.

WILLIAM LEE HANLEY, JR., OF BRADFORD, PENNSYLVANIA.

TUNNEL KILN.

Application filed February 10, 1925, Serial No. 8,093. Renewed June 16, 1926.

My invention consists in the novel features hereinafter described, reference being had to the accompanying drawings, which illustrate one embodiment of the same, selected by me for purposes of illustration, and the said invention is fully disclosed in the following description and claims.

The object of my invention is to provide a tunnel kiln which can be economically constructed and operated, and which will accommodate parallel goods conveying means so as to enable it to handle the largest possible output. To this end my improved kiln comprises a duplex firing chamber located centrally of the longitudinal length of the kiln and provided with two entirely separate firing zones, separated by a vertical, longitudinal partition wall, the kiln being provided with a unitary tunnel section extending longitudinally from each end of the duplex firing chamber and provided with parallel goods conveying means movable in opposite directions, each of which passes through one of the firing zones. In each of the firing zones is located a longitudinally disposed heating chamber, or muffle, or flue, which is preferably located adjacent to the outer wall of the zone, so that these heating chambers, or flues, are located on opposite sides of the duplex firing chamber, and as far as possible from the central partition wall. Heated products of combustion are introduced into each of the heating chambers, as by providing it at one end with a suitable burner, or burners, and I prefer to withdraw the products of combustion from each of said heating chambers at the opposite end thereof, and conduct them away from the kiln where they may be utilized for any desired purpose, as heating air for the burners, or heating a dry room, in which the bricks are given a preliminary drying before introducing them into the kiln, or for any other desired purpose, so as to conserve the useful heat units thereof. It will also be understood that the burner, or burners, for one of said heating chambers is located at the opposite end of its firing zone, from the position occupied by the heating burner, or burners, of the heating chamber in the adjacent zone.

In the operation of the kiln, the green bricks are introduced preferably on the cars or other movable conveying means on one track of the unitary tunnel section at one end of the kiln, and on the other track of

the other unitary tunnel section at the other end of the kiln, and the goods are moved longitudinally in opposite directions, passing through the unitary tunnel section, thence to one of the firing zones of the duplex firing chamber, and then through the other unitary tunnel section. It is highly important in the operation of a tunnel kiln that the temperature of each firing zone at the end where the goods enters the zone, shall be materially less than the hottest portion of the zone. For example, I prefer to so operate the heating chambers that the temperature at the entering end of each firing zone shall be approximately 1400° or 1500° F., while the hottest portion of the zone, which will be adjacent to the other end thereof, is maintained at approximately 1900° to 2000° F. As the cars move in opposite directions, it is obvious that the hottest end of one firing zone will be approximately opposite the less highly heated end of the other firing zone of the duplex firing chamber, and one of the objects of the central partition is to keep the two zones entirely separated and prevent the passage of any material amount of heat from one zone to the other so that this condition may be maintained at all times. For the same reason I also prefer, as before stated, to locate the longitudinal heating chambers, or muffles, as remotely as possible from the central longitudinal partition. It will also be understood that after the goods have traversed one of the firing zones, during which time they will be completely fired, they pass into one of the unitary tunnel sections and are carried therethrough toward the end thereof, gradually cooling and giving up their heat to the goods moving in the opposite direction on the other track, or carrier, which are gradually raised in temperature so that by the time they reach the cooler end of the firing zone for that carrier, they will have been brought up to substantially the minimum temperature of that of the entering portion of said firing zone. The same action takes place in both of the unitary tunnel sections, that is to say, a cooling of the fired products, which give off their heat so as to preheat the incoming products on the other track or carrier.

Referring to the accompanying drawings, which illustrate one form of kiln embodying my present invention,

Fig. 1 is a top plan view representing dia-

grammatically a kiln embodying my invention.

Fig. 2 is an enlarged horizontal section of the same, partially broken away at the 5 opposite end portions.

Fig. 3 represents an enlarged transverse sectional view of my improved kiln, taken on the line 3—3 of Fig. 2, through the duplex firing chamber, and illustrating one 10 form of heating chamber, or muffle, which may be used in the firing zones thereof.

Fig. 4 is a similar sectional view illustrating a different form of heating flue, or muffle.

Fig. 5 represents an enlarged sectional view on the line 5—5 of Fig. 2, through one 15 of the unitary end sections of my improved tunnel kiln.

Referring to the drawing, A, represents 20 the duplex firing chamber of my improved kiln, which is located centrally with respect to the length of the kiln, and is provided at each end with a unitary cooling and pre-heating chamber, one of which is indicated 25 at A', and the other of which is indicated at A². The duplex firing chamber is illustrated in section in Fig. 3. It comprises two exterior walls, 1—1, a central partition wall, 2, and separate crowns, 3—3, of any 30 usual or preferred construction, forming two tunnels, 4—4, separated by the partition wall, 2, each tunnel constituting a firing zone. At the outer side of each tunnel or zone is located a longitudinally extending 35 heating flue, indicated at 5, and in Fig. 3, I have shown this heating flue in the form of the well known "Dressler" flue, which is made in sections, as indicated in Fig. 2, of fire resisting material placed side by side 40 and providing the centrally located flues, 5—5, and surrounding air passages, 6, in the well known way. One of the flues, 5, is provided at one end with a burner, or burners, indicated at 7, and controlled by suitable 45 valve, or valves, indicated at 8, for discharging into the central flue the heated products of combustion which are withdrawn at the other end of the flue by means of a pipe, or pipes, 9, by means of which 50 they are conducted to a heat exchanging device for heating the air for the burner, so they may be conducted to a drying room and employed for preliminarily drying the bricks, or for any other purpose. Obviously 55 the highest temperature of the flue will be at the end adjacent to the burner, and in order to indicate this on the drawing, I have applied the temperature indication of 2000° F. at the end of the adjacent firing 60 zone nearest the burner, 7, and the temperature indication 1400° F. adjacent to the opposite or entering end therefrom. The heating flue, 5, of the other firing zone will be provided with a burner, 10, which is located at the opposite end of the duplex

firing chamber from the burner, 7, and the products of combustion from the flue are withdrawn at the opposite end of the firing zone, by a pipe, 11, and likewise conducted away and utilized in the manner before described. I have indicated, adjacent to this firing zone, the temperature of 2000° F. adjacent to the opposite end of the said firing zone heated thereby, on the drawing, Fig. 2, and 1400° at the other or entering 70 end thereof. I prefer to make the duplex firing chamber, A, of greater width than the interior tunnel sections, A'—A², and to locate the heating chambers, 5, adjacent to the outer walls, 1, of the duplex firing chamber, so as to have them as far as possible from the partition wall, 2, in order that the heat in each zone may be at all times controlled so that the hotter end of each zone is substantially opposite the cooler end of the other zone. 16—16 represent two separate tracks, or pairs of rails, which extend through the entire tunnel kiln, and preferably parallel to each other, passing side by side through the unitary tunnel sections, 80 and each track or pair of rails passing through one of the heating zones and being separated throughout the firing chamber by the centrally located partition, 2. Each of these tracks will be provided with a series 85 of cars, 17, extending from one end of the kiln to the other, and moving in opposite directions, as indicated by the arrows in Fig. 2, said cars carrying the brick or other coarse clay products, or other goods to be 90 fired. The cars on each track will be moved forwardly in the direction of the arrow applied thereto in Fig. 2, either continuously or intermittently, the green or unfired products being introduced into the kiln at the 95 outer ends of the unitary tunnel sections on their respective tracks, preferably by adding a car of the green products, and moving the entire train longitudinally of the kiln, and thereby discharging a car of 100 the fired and cooled products at the other end of the other unitary tunnel section. It will be seen that each of the unitary tunnel sections, A'—A², form combined cooling and preheating chambers, in which the fired 105 products leaving the duplex firing chamber on one track become gradually cooled and give up their heat by radiation and convection to the products moving in the opposite direction on the other track, and thereby raising the temperature thereof to approximately the temperature prevailing at the less highly heated end of the aligned 110 firing zone. The preheated goods then enter the respective firing zones of the duplex firing chamber from opposite ends thereof, and pass in opposite directions therethrough, becoming gradually hotter and hotter until complete firing is effected, 115 and passing from their respective zones 120

125 130

after firing, into one of the unitary tunnel sections to become cooled and to preheat the incoming goods on the other track, as previously set forth.

Fig. 4 represents a view similar to Fig. 3, in which the parts are given the same reference numerals with the reference letter "a" added. In this instance I have shown each of the firing zones, 4^a—4^a, of the duplex firing chamber provided with longitudinally disposed heating chamber, flue, or muffle, indicated at 5^a, formed of hollow tile composed of refractory material, in approximately triangular shape, as indicated, and arranged in each of said firing zones adjacent to the outer side thereof. I do not limit myself to any particular form of heating chamber, flue or muffle, for heating the firing zones, as any desired form of such heating chamber may be employed. As indicated in both Figs. 3 and 4, the central partition wall, 2 or 2^a, is a very substantial wall interposed between the two firing zones, so as to prevent any transfer of heat from one zone to the other sufficient to affect the graduation of temperature extending in opposite directions in said separate zones.

In Fig. 5 I have shown a cross section on the line 5—5 of Fig. 2, through one of the unitary tunnel sections, which consists of side walls, 18, and a single roof or crown, 19, extending above both sets of tracks, or rails, 16, supporting the cars, 17, side by side. In order to prevent injury to the car wheels and bodies, a centrally located platform, indicated at 20, is conveniently placed between the two tracks, but does not extend upward into the goods space, so that the parallel rows of goods are not separated from each other in any way, and the fired goods on one line of cars in cooling, will transfer their heat by radiation and convection, to the unfired goods on the other line of cars, and raise the temperature thereof, as before stated. It is unnecessary to provide any air forcing devices in connection with the unitary tunnel sections, as the same air can be used over and over again, and will circulate transversely of the tunnel section, by reason of the goods on one line of cars being hotter than those on the other line of cars, thus promoting a rapid and effective circulation within the tunnel section.

It will be noted that in this form of tunnel kiln, the products of combustion are kept out of contact with the goods to be conveyed as they are confined entirely to the heating chambers, flues or muffles, 5, (or 5^a). My improved tunnel kiln is therefore well adapted for firing those classes of goods which are liable to be injured by the direct contact therewith of heated products of combustion. It will be further noted that my improved tunnel kiln can be very inexpens-

sively constructed, as the greater portion thereof, to wit, the unitary tunnel sections, comprise simply lateral walls and a single crown, and being of substantially the cross section necessary to accommodate the two lines of goods passing therethrough, and the conveying means. The central portion of the duplex firing chamber is of somewhat more expensive construction, but is of comparatively short length, and by the use of my invention, the entire cost of the kiln can be brought within reasonable figures, thus obviating one of the greatest objections to twin tunnel kilns, which has been their practically prohibitive cost. It will also be seen that my improved kiln may be readily and economically operated and maintained in operative condition, and is capable of being operated continuously, so as to secure the highest possible output which is a matter of great importance, especially in the firing of brick and other coarse clay products.

It will be understood that the heating burners of the heating chambers, flues or muffles, can be regulated by means of suitable valves 8 (or 8^a) for example, or by any other suitable form of regulating means, so as to maintain at all times the graduation of temperature within the adjacent firing zone, the lowest temperature being at the end of the zone where the goods enter from one of the unitary cooling and preheating tunnel sections, and gradually increasing toward the other end (ordinarily that nearest the burners) where the greater heat prevails the gradation in the heat of each zone proceeding in opposite directions in the two firing zones.

It is also to be understood that I do not limit myself to the particular temperatures herein mentioned, as expressing the range of temperature in the respective firing zones from the entering end to the discharging ends thereof. The temperatures mentioned herein are merely recited as examples, and it will be understood that by means of the heat regulating means, such as valves 8, (or 8^a), or equivalent devices, other desired maximum and minimum temperatures may be maintained in the heating zones.

What I claim and desire to secure by Letters Patent is:—

1. In a tunnel kiln, the combination with a duplex firing chamber having two separate firing zones, separated by a longitudinally extending solid wall, a closed heating chamber extending longitudinally through each heating zone, and maintained out of communication therewith, said heating chambers being each provided with a heating burner for delivering products of combustion at one end and being provided at the opposite end with means for conducting the products of combustion from said heating chambers, a

- unitary tunnel section extending longitudinally from each end of the duplex firing chamber, and parallel goods conveying means movable in opposite directions and 5 each extending through each of said unitary end sections, and through one of the firing zones of the duplex firing chamber.
2. In a tunnel kiln, the combination with a duplex firing chamber having two separate 10 firing zones, separated by a longitudinally extending solid wall, a closed heating chamber extending longitudinally through each heating zone and being located on the other side of the goods space therein, and adjacent 15 to the exterior wall of the duplex firing chamber and maintained out of communication with the heating zone in which it is located, said heating chambers being each provided with a heating burner at one end 20 and at the opposite end with means for conducting the products of combustion therefrom, the heating burner of one heating chamber being located at the opposite end of the duplex firing chamber from the heat- 25 ing burner of the other heating chamber, whereby the temperature within the heating zones will be graduated from one end to the other thereof in opposite directions in said respective zones, a unitary tunnel section 30 extending longitudinally from each end of the duplex firing chamber, said kiln being provided with parallel goods conveying means movable in opposite directions, and each extending through each of said unitary 35 end sections through one of the firing zones of the duplex firing chamber.
3. In a tunnel kiln, the combination with a duplex firing chamber having two separate firing zones arranged side by side, and separated 40 by a central, longitudinally extending solid wall, a closed heating chamber extending longitudinally through each heating zone and located adjacent to the adjacent exterior wall of the duplex firing chamber, and main- 45 tained out of communication with the heating zone through which it passes, said heat-
- ing chambers being each provided with a heating burner at one end and at the other end with means for conducting the products of combustion therefrom, the heating burner 50 for the heating chamber of each zone being located at the opposite end of the duplex firing chamber from the heating burner for the heating chamber of the other zone, a unitary tunnel section extending longitudi- 55 nally from each end of the duplex firing chamber, and parallel goods conveying means movable in opposite directions and extending through each of said unitary end sections and through one of the firing zones 60 of the duplex firing chamber, between the heating chamber therein and the centrally located wall.
4. In a tunnel kiln, the combination with a duplex firing zone having two separate 65 firing zones separated by a centrally located longitudinal, impervious wall, a closed heat- 70 ing chamber extending through each of said zones, heating means for each of said heating chambers, heat regulating means for said 75 heating means for maintaining gradually increasing temperatures from one end of each zone to the other, said graduation of temperatures proceeding in opposite direc- 80 tions in said respective zones, a unitary tunnel section extending longitudinally from each end of said duplex firing chamber, and parallel goods conveying means movable in opposite directions and extending through each of said unitary tunnel sections and 85 through one only of the firing zones of the duplex firing chamber, said conveying means transporting the preheated unfired goods into the aligned firing zone at the end thereof wherein the minimum temperature is maintained, and discharging the fired goods from the end of said zone adjacent to the point or points where the maximum temperature is maintained.

In testimony whereof I affix my signature.

WILLIAM LEE HANLEY, JR.
